UNITED STATES PATENT OFFICE.

ITHAMAR M. JUSTICE, OF DAYTON, OHIO, ASSIGNOR TO THE MANUFACTURERS EQUIPMENT COMPANY, OF DAYTON, OHIO, A CORPORATION OF OHIO.

PROCESS IN DIRECT-ACTION DRIERS.

1,393,788.

Specification of Letters Patent.

Patented Oct. 18, 1921.

Application filed May 3, 1919. Serial No. 294,499.

To all whom it may concern:

Be it known that I, ITHAMAR M. JUSTICE, a citizen of the United States, residing at Dayton, in the county of Montgomery and 5 State of Ohio, have invented certain new and useful Improvements in Processes in Direct-Action Driers, of which the following is a specification, reference being had therein to the accompanying drawing.

10 This invention consists of an improved process of manufacturing relating to direct action driers for ceramic products and has for its particular object to provide a process of manufacturing which may be applied 15 most effectually in direct action driers shown in one preferred form of construction in my copending application for Letters Patent, Ser. No. 294,498, filed May 3rd, 1919.

The new process is especially applicable to 20 driers constructed to have the air which carries off the moisture from the product as it is treated in the drying tunnels introduced at the receiving end of the tunnels and therefore movable in the direction the product is 25 moved through the tunnels.

Under the preferred arrangement the furnaces are located at the end of the driers opposite the receiving end, the heat being conducted through underground heating tunnels 30 extending parallel with the drying tunnels substantially the full length of the latter, and then conducted upwardly through suitable flues to heating channels communicating with a stack located, preferably, approximately at the central portion of the 35 structure. By such an arrangement the maximum amount of heat radiation is obtained in the drying tunnels from below and above, and the air passing therethrough is maintained at even temperatures which 40 gradually increase from warm or comparatively low temperatures at the receiving end of the drying tunnels to hot or relatively high temperature at the delivering end.

45 With the gradual increase in temperature of the air as it passes through the drying tunnels, its moisture carrying capacity is increased accordingly but in greatly increased proportion.

50 It is a well known physical law that at 42° F. one pound of air will carry .089 oz. of moisture; at 82°, .38 oz.; at 132°, 1.88 oz. and at 182°, 11.4 oz. Thus it will be observed that the increase in moisture carrying

properties of the air is very great with a 55 relatively small increase in temperature.

In the application of this natural law of evaporation, it is well known that if the air in a process of drying conducted on this principle leaves the tunnel at 162° F., the 60 weight necessary to carry one pound of water is only 3.1 pounds or 48½ cubic feet, as compared with 50½ pounds or "89 cubic feet required in a drier operated on the inverse system, *i. e.*, in which the air moves 65 opposite the direction the product is moved through the tunnels, and working between 82° and 170°.

Therefore, by means of my improved process the drying operation is greatly facilitated, is much more uniform, and less liable to cause waste in the finished product by cracking, as the moisture carrying capacity of the air increases so rapidly with the gradual increase in temperature that there 75 is no condensation on the ware.

Most clays, including the delicate or tender grades, may be dried under the improved process in the comparatively short time of thirty hours, thus effecting a large saving in 80 fuel as well as improving the quality of the product and minimizing the usual waste resulting from cracking which are inevitable under constructions and processes where the inverse system is practised.

Under my improved process during the greater part of the drying operation the air is so charged with moisture as to be nearly saturated; the increase in temperature being gradual and uniform, strong air currents 90 and excessive surface drying are avoided, and delicate clays, which inevitably crack under the inverse system of drying, may be successfully treated by the new process with a minimum of waste and otherwise highly 95 satisfactory results.

An important step in the new process of direct action drying is provided for by locating the stack intermediate the receiving and delivering ends of the drying tunnels. 100 By such an arrangement the hot moisture laden air as it rises from the hot end of the tunnels is carried, as shown in the present arrangement, through channels leading to the stack and extending parallel with the 105 drying tunnels, thus acting to heat the ceilings of the tunnels and aiding thereby to maintain the uniformity of temperature

within the tunnels which is so essential to obtaining the best results with the product.

While the principle of direct action drying by introducing the air at atmospheric temperature at the receiving end of the drying tunnels and causing it to pass therethrough in the same direction as the product, is not broadly new *per se*, the particular steps of the present process of treatment in various important particulars are new and tend to bring about results which, considered separately and as a whole, are a marked improvement over the earlier practice with respect to the shorter time required for the drying operation, the reduction in fuel requirements, and the reduction in waste or loss in the finished product.

In the accompanying drawings a construction of an improved type is illustrated in one form in which the present invention may be effectually applied. Driers of the type shown are usually of large construction consisting of a plurality of drier units, all of which are essentially alike in construction and general arrangement.

As here shown:—

Figure 1 illustrates a side elevation taken in longitudinal section, and showing the arrangement of the furnaces, the fuel and drying tunnels and the channels of air passages leading therefrom to the common stack.

Fig. 2 is a cross sectional view taken on the line 2—2 of Fig. 1, and looking in the direction of the arrows.

Fig. 3 is a cross section view taken on the line 3—3 of Fig. 1, having the upper portion of the stack broken away.

Fig. 4 is a plan view in cross section of the receiving end of the dryer taken on the line 4—4 of Fig. 3.

Fig. 5 is an enlarged detailed plan view taken on the line 5—5 of Fig. 1; and

Fig. 6 is an enlarged detailed view in elevation of the upper portion of one of the heat flues.

The process as practised in a construction of the character shown consists in heating the furnaces 1, in any suitable manner as by coal or gas fuel, and in conducting the heat from the furnaces through the tunnels 2 into cross tunnels or chambers 3, and thence upwardly through flues 4 into the heating or dry air channels 5, which extend parallel with the drying tunnels 6 and lead direct into the stack 7. The metal arch 8 and ceilings 9 of the drying tunnels are thus heated by radiation, the temperature within the driers increasing gradually from the end of the tunnels farthest removed from the furnaces, which is known as the cold end of the driers, to the opposite end which is known as the hot end. Partition walls 10, 11, 12 and 13 are interposed respectively between the different units of the fuel and drier tun-

nels and the draft channels leading to the stack.

A further step in the process consists in introducing the air, which absorbs and carries off the moisture from the product, at atmospheric temperature to the drying tunnels at their cold ends, and causing the air to pass through the driers in the same direction as the product is moved, the air being gradually increased in temperature by the heat radiated from the floor, side walls and ceiling of the tunnels and absorbing relatively greater quantities of moisture until the highest temperature required in the process is attained at the hot end of the tunnels; the saturated air then passing upward through suitable draft apertures in the ceilings of the tunnels is conducted through channels 14 extending parallel with the drying tunnels and leading direct into the stack 7. A partition wall 15 serves to divide the dry air channels 5 and moist air channels 14 to prevent intermingling of the two atmospheres until they pass upwardly into the stack. This arrangement is for the purpose of maintaining uniformity of temperatures, to prevent condensation of the moist atmosphere, and to improve the draft.

By means of air pits 16 and air passages 17 leading therefrom into the cold ends of the drier tunnels the supply of fresh air to the tunnels at atmospheric temperature is constant, the quantity being regulated by the size of the opening 18 in the wall 19. It is an important feature of the process to supply the quantity of air required to obtain the best results in drying. This is determined by experience and should be regulated to suit the character of clay used in the product. It is a further feature of the process to maintain temperatures, by properly balanced heating and draft regulations, that will cause the air to be near saturation at all points in its passage through the drying tunnels. Thus the drying process is maintained relatively uniform to the variations in temperature and the law of increase in its moisture carrying qualities, and the process proceeds and arrives at completion in the shortest time and with the minimum of fuel consumption.

In the application of the process the drying tunnels are provided with the usual tracks 20, and any suitable trucks or cars may be used for supporting the ware and carrying the same through the drying process, the ends of the tunnels being closed in the usual manner by doors 21.

Having thus fully described my invention, what I claim as new and desire to secure by Letters Patent, is:—

1. The herein described process of heat treating materials in a drying tunnel having beneath and parallel therewith a heating tunnel connecting at one end with a fur-

- nace, said heating tunnel being provided at the end opposite the furnace with a flue extending upwardly to heating channels parallel with said drying and heating tunnels and leading to a stack intermediate the ends of the drying tunnel and there being also at the furnace end of the drying tunnel an outlet for the air therein opening into a channel leading to the stack; the process 10 consisting of passing a heating medium through the heating tunnel thence upwardly through the end flue to and along the heating channels to the stack; in introducing air at atmospheric temperature into the end 15 of the drying tunnel opposite the furnace end of the heating tunnel, and conducting it therethrough and upwardly near the furnace end thereof into and through the air channel extending to the stack, in introducing 20 into the drying tunnel the material to be treated and in advancing it therealong in the direction of the air current.
2. The herein described process of heat treating materials in a drying tunnel having beneath and parallel therewith a heating tunnel connecting at one end with a furnace, said heating tunnel being provided at the end opposite the furnace with a flue extending upwardly to heating channels parallel 30 with said drying and heating tunnels and leading to a stack intermediate the ends of the drying tunnel and there being also at the furnace end of the drying tunnel an outlet for the air therein opening into a channel leading to the stack; the process 35 consisting of passing a heating medium through the heating tunnel thence upwardly through the end flue to and along the heating channels to the stack; in introducing air at 40 atmospheric temperature into the end of the drying tunnel opposite the furnace end of the heating tunnel, and conducting it therethrough and upwardly near the farther end thereof into and through an air channel extending 45 over the drying tunnel to the stack, in introducing into the drying tunnel the material to be treated and in advancing it therealong in the direction of the air current.
- 50 3. The herein described process of heat treating materials in a drying tunnel having beneath and parallel therewith a heating tunnel connecting at one end with a furnace, said heating tunnel being provided 55 at the end opposite the furnace with a flue extending upwardly to heating channels parallel with said drying and heating tunnels and leading to a stack intermediate the ends of the drying tunnel and there being 60 also at the furnace end of the drying tunnel an outlet for the air therein opening into a channel leading to the stack; the process consisting of passing a heating medium through the heating tunnel thence upwardly 65 through the end flue to and along the heat-
- ing channels to the stack; in introducing air at atmospheric temperature into the end of the drying tunnel opposite the furnace end of the heating tunnel, and conducting it therethrough and upwardly near the furnace 70 end thereof into and through the air channel extending over and parallel with the drying tunnel to the stack, in introducing into the drying tunnel the material to be treated and in advancing it therealong in the direction 75 of the air current.
4. The herein described process of heat treating materials in a drying tunnel having beneath and parallel therewith a heating tunnel connecting at one end with a furnace, said heating tunnel being provided at the end opposite the furnace with a flue extending upwardly to heating channels parallel with said drying and heating tunnels and leading to a stack intermediate the 80 ends of the drying tunnel and there being also at the furnace end of the drying tunnel an outlet for the air therein opening into a channel leading to the stack; the process 85 consisting of passing a heating medium through the heating tunnel thence upwardly through the end flue to and along the heating channels to the stack; in introducing air constantly at atmospheric temperature 90 into the end of the drying tunnel opposite the furnace end of the heating tunnel, and conducting it therethrough and upwardly near the furnace end thereof into and through the air channel extending over the 95 drying tunnel to the stack, in introducing 100 into the drying tunnel the material to be treated and in advancing it therealong in the direction of the air current.
5. The herein described process of heat treating materials in a drying tunnel having beneath and parallel therewith a heating tunnel connecting at one end with a furnace, said heating tunnel being provided at the end opposite the furnace with a flue extending upwardly to heating channels parallel 105 with said drying and heating tunnels and leading to a stack intermediate the ends of the drying tunnel and there being also at the furnace end of the drying tunnel 110 an outlet for the air therein opening into a channel leading to the stack; the process 115 consisting of passing a heating medium through the heating tunnel thence upwardly through the end flue to and along the heating channels to the stack; in introducing air 120 at atmospheric temperature in regulated quantities into the end of the drying tunnel opposite the furnace end of the heating tunnel, and conducting it therethrough and upwardly near the furnace end thereof into 125 and through the air channel extending over the drying tunnel to the stack, in introducing into the drying tunnel the material to be treated and in advancing it therealong in the direction of the air current.

6. The herein described process of heat treating materials in a drying tunnel having beneath and parallel therewith a heating tunnel connecting at one end with a furnace, said heating tunnel being provided at the end opposite the furnace with a flue extending upwardly to heating channels parallel with said drying and heating tunnels and leading to a stack intermediate the ends 5 of the drying tunnel and there being also at the furnace end of the drying tunnel an outlet for the air therein opening into a channel leading to the stack; the process consisting of passing a heating medium 10 through the heating tunnel thence upwardly through the end flue to and along the heating channels to the stack; in introducing air constantly at atmospheric temperature in regulated quantities into the end of the drying 15 tunnel opposite the furnace end of the heating tunnel, and conducting it therethrough and upwardly near the furnace end thereof into and through the air channel extending over and parallel with the drying 20 tunnel to the stack, in introducing into the drying tunnel the material to be treated and in advancing it therealong in the direction of the air current.

7. The herein described process of heat 30 treating materials in a drying tunnel having beneath and parallel therewith a heating tunnel connecting at one end with a furnace, said heating tunnel being provided at the end opposite the furnace with a flue extending 35 upwardly to heating channels parallel with said drying and heating tunnels and leading to a stack intermediate the ends of the drying tunnel and there being also at the furnace end of the drying tunnel an outlet for the air therein opening into a channel 40 leading to the stack; the process consisting of passing a heating medium through the heating tunnel thence upwardly through the end flue to and along the heating 45 channels to the stack; in introducing air at atmospheric temperature in regulated quantities into the end of the drying tunnel opposite the furnace end of the heating tunnel, in causing the same to be gradually increased 50 in temperature by radiation of heat as it passes therethrough and in conducting it upwardly near the furnace end thereof into and through the air channel extending over and parallel with the drying tunnel to 55 the stack, in introducing into the drying tunnel the material to be treated and in advancing it therealong in the direction of the air current.

8. The herein described process of heat 60 treating materials in a drying tunnel having

beneath and parallel therewith a heating tunnel connecting at one end with a furnace, said heating tunnel being provided at the end opposite the furnace with a flue extending upwardly to heating channels parallel 65 with said drying and heating tunnels and leading to a stack intermediate the ends of the drying tunnel and there being also at the furnace end of the drying tunnel an outlet for the air therein opening into a channel 70 leading to the stack; the process consisting of passing a heating medium through the heating tunnel thence upwardly through the end flue to and along the heating channels to the stack; in introducing air at atmospheric 75 temperature in regulated quantities into the end of the drying tunnel opposite the furnace end of the heating tunnel, in causing the same to be gradually increased in temperature by radiation of said heat and 80 to be maintained approximately at the point of saturation as it passes through the drying tunnel upwardly near the furnace end thereof into and through the air channel extending to the stack, in introducing into the drying 85 tunnel the material to be treated and in advancing it therealong in the direction of the air current.

9. The herein described process of heat 90 treating materials in a drying tunnel having beneath and parallel therewith a heating tunnel connecting at one end with a furnace, said heating tunnel being provided at the end opposite the furnace with a flue extending 95 upwardly to heating channels parallel with said drying and heating tunnels and leading to a stack intermediate the ends of the drying tunnel and there being also at the furnace end of the drying tunnel an outlet for the air therein opening into a channel 100 leading to the stack; the process consisting of passing a heating medium through the heating tunnel thence upwardly through the end flue to and along the heating channels to the stack; in introducing air at atmospheric 105 temperature in regulated quantities into the end of the drying tunnel opposite the furnace end of the heating tunnel, in causing the same to be gradually increased in temperature by radiation of said heat and 110 to be maintained slightly below the point of saturation as it passes through the drying tunnel upwardly near the furnace end thereof into and through the air channel extending to the stack, in introducing into the drying 115 tunnel the material to be treated and in advancing it therealong in the direction of the air current.

In testimony whereof I affix my signature.
ITHAMAR M. JUSTICE.
